UNITED STATES PATENT OFFICE

HANS HENRIK CHRISTIAN GRONDAHL, OF CHICAGO, ILLINOIS, ASSIGNOR TO WESTERN ELECTRIC COMPANY, INCORPORATED, OF NEW YORK, N. Y., A CORPORATION OF NEW YORK

CARRIER

Application filed July 31, 1926. Serial No. 126,168.

This invention relates to carriers, and more particularly to carriers for use with cranes or other hoisting apparatus.

In transferring loads by the use of cranes and the like, load engaging carriers suspended by the crane cable, are employed and in many instances these carriers are adapted to handle particular types of loads. Thus, for example, where the load consists of heavy material such as large metallic sheets or material supporting pans, the carrier should be adapted to engage with and support the load in such a manner that the load will be securely held in position and the weight or bulk thereof will be evenly distributed upon the carrier. Sheet supporting pans and like materials are in their very nature cumbersome because of the wide distribution of their bulk and therefore in the process of transferring or lifting such materials by the use of a crane cable, care must be used in arranging them in a balanced position at the end of the cable.

The primary object of this invention is to facilitate and accelerate the lifting and transferring of loads by the provision of an inexpensive, durable and efficient load engaging carrier for use in connection with hoisting and traveling apparatus.

In accordance with the general features of the invention one embodiment thereof comprises a rigid frame which is adapted to be suspended from a crane cable by means of a swivel. The frame supports a plurality of oppositely disposed depending arms pivoted thereto, and which carry elongated clamping members at their lower extremities for engaging with and supporting heavy loads having wide bulk distribution such as large shallow pans filled with heavy materials or various forms of metallic sheet materials. These arms may be swung into and out of engagement with respect to a load by a leverage mechanism which is manually operable from opposite points with respect thereto. In one form of carrier embodying the invention hand wheels at each end of the carrier frame are geared with the means for actuating the pivoted

arms, thereby greatly facilitating the handling of materials. In another form a pair of centrally positioned and oppositely disposed hand levers are adapted to be conveniently operated by a worker for actuating the arms of the carrier in loading and unloading materials.

These and other objects will be more apparent from the following detailed description and the accompanying drawings, wherein

Fig. 1 is a plan view of a carrier disclosing one embodiment of the invention;

Fig. 2 is a transverse vertical sectional view of the carrier taken on line 2-2 of Fig. 1;

Fig. 3 is a fragmentary side elevation of the carrier shown in Fig. 1;

Fig. 4 is a plan view of an alternate form of the carrier disclosed in Fig. 1;

Fig. 5 is a transverse vertical sectional view taken on the line 5-5 of Fig. 4, and

Fig. 6 is a fragmentary side elevational view of the carrier shown in Fig. 4.

Referring now to the drawings wherein like numerals have been employed to designate similar parts throughout the various disclosures, it will be observed that the carrier disclosed in Figs. 1, 2, and 3 includes a rectangular frame 10. Secured to this frame 10 at each corner thereof and at points medially of its sides are the lower extremities of support members 11 which are inclined upwardly and inwardly from the frame 10. The upper extremities of the support members 11 are suitably secured to a coupling 13 of a swivel 15. This swivel 15 comprises a ring 16, a shank 17 depending therefrom and extending through the coupling 13 and a nut 18 threaded upon the lower extremity of the shank 17. The ring 16 is adapted to accommodate conventional types of hooks and the like (not shown) carried by crane cables.

Secured at each end of the sides of the frame 10 are brackets 20 and secured medially of the sides are brackets 21. These brackets 20 and 21 serve as a mounting for rotatable shafts 22. Positioned adjacent to the brackets 20 and secured to the shafts 22

90

95

100

are carrier arms 24 which are each formed with an upper portion 25 and a lower depending portion 26. Positioned at each bracket 21 and secured to the shaft 22 is a depending carrier arm 28, the lower extremities of the arms 24 and 28 being formed to support a pair of parallel clamping members 29 of angular cross section.

Extending longitudinally and medially above the frame 10 is an actuating rock-shaft 31 which is rotatably mounted at its ends in bearing members 32 secured to the end portions of the frame 10. Mounted upon the actuating shaft 31, adjacent to each of the bearings 32, are gears 34 which mesh with companion pinion gears 35 disposed therebeneath, the pinions being mounted upon stub shafts 37 (Fig. 2). Each of these stub shafts 37 is revolvably mounted in the bearing members 32 and supports a hand wheel 38 at its outer extremity. Oppositely disposed rocker arms or lever arms 40 secured to the actuating shafts 31 adjacent each of the gears 34 are connected at their extremities with the ends of the upper portions 25 of the arms 24 by means of links 41.

From the foregoing it will be apparent that by turning either of the hand wheels 38 in one direction the depending portions 26 of the arms 24 will be swung outwardly through the medium of the pinion 35, the gear 34, the arms 40 and the links 41, and by turning the hand wheel 38 again in a reverse direction the arms 24 will be swung inwardly. When the links 41 and the arms 40 are in alignment as shown in Fig. 2, the lower depending portions 26 of the arms 24 will have been swung together to their innermost position and it will be apparent that they cannot be swung outwardly again without breaking the alignment of the arms 40 and the links 41 by the manipulation of the hand wheel 38.

The carrier disclosed in Figs. 4, 5, and 6 represents an alternate form of the carrier heretofore described and comprises a similar frame 10, support members 11 and swivel 15 to which the upper end of the support members are secured. Brackets 20 are secured at each end of the sides of the frame 10 and brackets 21 are secured medially of said frame. These brackets 20 and 21 support a pair of rotatable shafts 22 and a plurality of arms 44 are secured to and depend from each of these shafts 22. The lower extremities of the arms 44 are formed to support clamping members 29 similar to those described in connection with the carrier shown in Figs. 1, 2, and 3.

Traversing the central portion of the frame 10 (Fig. 5) is a cross bar 46 which has a bearing plate 47 secured thereto and extending upwardly therefrom. The upper end of the bearing plate supplies a bearing 65 for the inner ends of oppositely disposed

lever arms 49 which are pivoted to the bearing plate 47 at 50. The inner extremities of these lever arms 49 are formed with cooperating similar gear segments 52. Lateral projections 53 formed on the lever arms 49 are connected at their extremities to the upper ends of actuating arms 54 carried by the shafts 22 through the medium of links 55.

From the foregoing it will be clear that when the lever arms 49 are raised from their horizontal position shown in Fig. 5 the arms 44 will be swung outwardly through the action of the arms 54, the links 55, the projections 53 and the gear segments 52. When the lever arms 49 are again returned to their horizontal position, the arms 44 will have been swung together to their innermost positions and lugs 56 projecting from each of the lever arms 49 prevent the arms 44 from being swung outwardly until the lever arms are again raised. It will be apparent that the lever arms 49 are so positioned that they may very conveniently be operated individually from either side of the frame and the operator may be in a position clear of the supported load.

In the operation of the carrier disclosed in Figs. 1 to 3 inclusive when said carrier is being lowered or carried into association with a pan or stack of sheet metal by means of a suitable crane, one of the hand wheels 38 is manipulated so as to swing the lower portions 26 of the arms 24 outwardly to permit the lowering of the clamping members 29 over the sides of the material to be engaged. When the clamping members 29 have been properly positioned with respect to the material the hand wheel 38 is again operated to swing the arms 24 inwardly, thereby carrying the clamping members 29 into operative engagement beneath the load such as a stack of sheets, shown in dot and dash lines, Fig. 2. When the links 41 and the oppositely disposed arms 40 are in alignment the arms 24 will be locked in their engaged position and the load may be hoisted and transferred without any possibility of the clamping members 29 becoming disengaged until the hand wheel 38 is again manually manipulated.

The operation of the carrier disclosed in Figs. 4 to 6 inclusive is quite similar to the operation just described except that the lever arms 49 instead of hand wheels are manipulated to actuate the arms 44. In both instances the carriers are designed to be operated by manipulating one of the lever arms 49 or the hand wheels 38 from the sides of the carrier frame or in other words at opposite points with respect to the load supported by the clamping members 29 and entirely clear thereof. By reason of this structure the worker is able to readily operate the carrier in loading and unloading

material of the class described with a minimum possibility of injury.

Although the invention as herein illustrated and described is particularly well adapted for use in connection with carrier devices for cranes and other hoisting apparatus, it should be understood that the novel features thereof are capable of other applications and should be limited only by the scope of the appended claims.

10 What is claimed is:

1. In a carrier, a frame, arms pivotally mounted on the frame, clamping members carried by the arms, a rock-shaft, means operable from opposite sides of the frame for rocking the shaft, and means for connecting the pivoted arms with the rock-shaft to effect positive rocking of the arms in either direction and for locking the arms in clamping position.

2. In a carrier, a frame for attachment with a hoisting apparatus, oppositely disposed arms pivotally mounted on the frame, elongated clamping members supported by the arms for engagement with a load, a rock-shaft disposed centrally of the frame, means operable from opposite sides of a carried load and at the ends of the shaft for rocking the shaft, and a leverage mechanism connecting the pivoted arms with the shaft to effect positive rocking of the arms in either direction and for locking the arms in clamping position.

3. In a carrier, a frame, a frame supporting means having a swivel for attachment with a hoisting apparatus, oppositely disposed arms pivotally mounted on the frame, elongated clamping members supported by the arms for engagement with a load to be carried, a rock-shaft disposed centrally of the frame, rotatable members operable from opposite sides of a carried load, gears connecting the ends of the shaft with the rotatable members, and a leverage mechanism connecting the pivoted arms with the shaft to effect positive rocking of the arms in either direction and for locking the arms in clamping position.

4. In a carrier, a frame, an arm pivotally mounted on one side of the frame, an arm pivotally mounted on another side of the frame and at diametrically opposite points to the first arm, clamping members carried by the arms, a shaft of smooth outline, means for imparting motion to the shaft, and means for connecting the pivoted arms with the shaft to effect positive rocking of the arms in either direction and for locking the arms in clamping position.

5. In a carrier, a frame, a plurality of sets of depending arms, the arms of each set secured to said frame at diametrically opposite points, and means operatively connected to said arms for effecting the positive operation of all of the arms of a set in the

same direction to either grapple material or to release the material and for locking the arms in grappling position.

6. In a carrier, a frame, grappling arms depending from the frame, a shaft for actuating the arms, rocker-arms attached to the shaft, and links connecting the rocker-arms with the grappling arms, said rocker-arms and links arranged to be in longitudinal alignment when the grappling arms are grasping material to lock the grappling arms in position.

7. In a carrier, a frame, a frame supporting means for attachment with a hoisting apparatus, oppositely disposed arms pivotally mounted on the frame and adapted to engage a load to be carried, a rock shaft mounted on the frame, rotatable members operable from portions of the frame remote from each other, gears connecting the rotatable members with the shaft, and a leverage mechanism connecting the pivoted arms with the shaft to effect positive rocking of the arms in either direction and for locking the arms in clamping position.

8. In a carrier, an elongated frame having supporting means for attachment to a hoisting apparatus, a rock shaft extending longitudinally of the frame, oppositely disposed arms pivotally mounted on the frame, elongated clamping members supported by the arms for engagement with a load to be carried, rotatable members operable from opposite sides of a carried load, gears connecting the rotatable members with the shaft, and a leverage mechanism connecting the pivoted arms with the shaft to effect a positive rocking of the arms in either direction and for locking the arms in clamping position.

In witness whereof, I hereunto subscribe my name this 16 day of July A. D., 1926.

HANS HENRIK CHRISTIAN GRONDAHL.
